UNITED STATES PATENT OFFICE.

WILLIAM J. LAUSTERER, OF JAMESTOWN, NEW YORK, ASSIGNOR TO U. S. STANDARD VOTING MACHINE COMPANY, OF ROCHESTER, NEW YORK, A CORPORATION OF NEW YORK.

KEY-LOCKING MECHANISM FOR VOTING-MACHINES.

No. 857,811.

Specification of Letters Patent.

Patented June 25, 1907.

Application filed January 2, 1906. Serial No. 294,068.

To all whom it may concern:

Be it known that I, WILLIAM J. LAUSTERER, of Jamestown, in the county of Chautauqua and State of New York, have invented certain new and useful Improvements in Key-Locking Mechanism for Voting-Machines; and I do hereby declare the following to be a full, clear, and exact description of the same, reference being had to the accompanying drawings, forming a part of the specification, and to the reference-numerals marked thereon.

My present invention relates to voting machines of the class embodying straight ticket mechanism for moving simultaneously to voted position the indicators or keys devoted to candidates of the same political party, and has for its objects to provide mechanism for locking the indicators or keys as soon as the movement of the operating mechanism of the machine commences, whereby not only is unlawful voting prevented, but the parts of the machine are so locked as to prevent the breakage of any of the parts. This result is accomplished best by locking the straight ticket indicating mechanism, and in the present embodiment of my invention I prefer to apply it to the type of machine shown in certain pending applications filed by A. J. Gillespie and others, in which the registers and indicators are moved relatively to operate the registers whose indicators are left in voted position.

The invention further consists in certain combinations and arrangements of parts all as will be fully described, the novel features being pointed out in the claims at the end of the specification.

In the accompanying drawings: Figure 1 is a rear elevation of a portion of the front plate of the voting machine provided with my improvements. Fig. 2 is a vertical sectional view on the line $x-x$.

Similar reference numerals in the figures indicate similar parts.

The individual candidate keys, the registers and operating mechanism therefor are of the general type shown in the patent to Gillespie, No. 799,556, for register or counter, said indicator being pivotally mounted on the front plate 1 provided with the segmental arms 2 in rear of which are the abutments 3,

said arms and abutments being adapted to coöperate with the actuator or pallet bar 5 of the register 6 mounted in the register frame 7 which is moved toward and from the front plate of the machine by suitable operating means such, for instance, as levers 8 pivoted to the main casing and having pins 9 operating in slots 10 formed in the sides 60 of the frame.

12 indicates straight ticket bars extending beneath the indicators being devoted to candidates for the same political party, said bars being suspended upon links or cranks 13 one 65 of which constitutes the operating lever. The ends of these straight ticket bars 12 are beveled and are adapted to coöperate with abutments or rollers 14 mounted upon a vertically movable universal bar 15, the parts 70 being so arranged that upon the operation of any of the straight ticket bars said universal bar will be moved vertically. This universal bar may or may not control other operating parts of the machine, but for the purposes of 75 the present invention it is sufficient that it is required to be moved by any of the straight ticket bars. The upper portion of this bar is provided with a serrated surface 17 which is adapted to engage a locking pawl or detent 18 80 pivoted at 16 and adapted to be swung into locking engagement with the universal bar either by gravity or a suitable spring, if desired. Upon the free end of the pawl or detent is provided a pin 22 upon which are loosely pivoted 85 two links 23 and 24, the former extending diagonally downward and having its lower portion guided upon a stationary pin 26 and the link 24 being pivoted to the inner end of the lever 25 pivoted upon the pin 26 90 and having its outer end projecting a distance above the end of the link 23. The detent or pawl 18 is adapted to engage and lock the universal bar and the straight ticket bars also at all times after the movement of the 95 register frame mechanism toward the indicators has commenced and said pawls should be released only when the straight ticket mechanisms are properly operable. The reason for this is that if the candidate indicators should be turned after the register frame had moved toward the indicator support the abutment on the indicator engaging beneath the projection on the end of the reg-

ister actuator might bend the latter and break or disarrange the mechanism. The proper release of the pawl or detent is accomplished by providing upon the vertically movable bar 19, connected to the register frame-actuating lever 8, the stops or projections 20 and 21, the former is adapted to engage the lever 25 to lift the pawl out of engagement when the rod is depressed, but at this time the straight ticket keys and the individual candidate keys are all held locked by the main resetting bar of the machine which coöperates with the interlocking straps 30, said resetting bar being connected to or operated by the bar 19, and while the machine is in that condition the straight ticket key cannot be operated, although the pawl is out of engagement. The unlocking of the universal bar 15 is secured at this moment for the purpose of permitting its operation to release other locking mechanisms of the machine, which are controlled by said bar, but specific description is unnecessary herein. The stud or projection 21 on the bar 19 is adapted when the bar is raised to engage with the lower end of the link 23 to lift the pawl out of engagement, when the keys can be moved to voted position in the proper manner and by the operation of the straight ticket keys or indicators, but as soon as the operating mechanism of the register frame starts to move, this lug 21 moves out of contact with said link, dropping the pawl and thus engaging the universal bar, as described, prevents the operation of any of the straight ticket indicators or keys until the operation is completed. The rack 17 on the universal bar is made purposely long so that if a voter should hold a straight ticket indicator or key partially operated during the return movement of the operating mechanism, the instant he returns the straight ticket key or indicator the bar 15 will follow it down and take a fresh hold on the pawl as it follows it, and this will prevent any backward movement whatever on the part of said bar.

I claim as my invention:

1. In a voting machine, the combination with a plurality of series of registers, a plurality of series of ballot indicators therefor, operable to voted position without actuating the registers and means for actuating the registers whose indicators are in voted position, of operating devices for the several series of indicators and means for locking all said operating devices during the movement of the register actuating means.

2. In a voting machine, the combination with a plurality of series of registers, a plurality of series of ballot indicators therefor, operable to voted position without actuating their registers and means for actuating the registers whose indicators are left in voted position, of an operating device for each of the several series of indicators and automatic

locking means for securing the said operating devices during the movement of the register actuating means and controlled by the latter to release said devices when in one position.

3. In a voting machine, the combination with a plurality of series of registers, a plurality of series of ballot indicators therefor, operable to voted position without actuating their registers and means for actuating the registers whose indicators are left in voted position, of an operating device for each of the several series of indicators, an automatic locking device for securing said operating devices with which the register actuating device coöperates to release said operating devices when in one position. 70 75 80

4. In a voting machine, the combination with a plurality of series of individual candidate indicators, a corresponding plurality of series of registers, straight ticket voting devices for operating the indicators of each series and actuating devices for the machine, of devices for locking the straight ticket operating devices and means for releasing said locking device when the actuating device is in 90 one position. 85 90

5. In a voting machine, the combination with a plurality of series of separately operable candidate indicators, a plurality of series of registers, means for operating the different series of indicators and means for actuating the registers whose indicators are left in voted position, of means for locking the series-operating devices during the movement of the actuating means. 95 100

6. In a voting machine, the combination with the actuating mechanisms, pluralities of series of indicators and registers, means for operating the series of indicators separately and a member operable by any of said series operating devices, of locking devices for securing said member from operation controlled by the actuating mechanism of the machine. 105

7. In a voting machine, the combination with a plurality of candidate voting mechanism, straight ticket mechanism and an actuating mechanism for the machine, of a lock for said straight ticket mechanism adapted to be released by the actuating mechanism when in 110 115 one position.

8. In a voting machine, the combination with a plurality of candidate voting mechanisms, a plurality of straight ticket voting mechanisms and actuating mechanism for the machine, of a member operable by any of the straight ticket mechanisms, an automatic lock therefor and releasing mechanism operable by the actuating mechanism. 120

9. In a voting machine, the combination with the straight ticket bars, and the universal bar operable by the latter, of an actuating mechanism for the machine, a pawl for securing the universal bar and connections between said pawl and the actuating mechan- 125 130

ism for holding it out of action when the actuating mechanism is in two different positions.

10. In a voting machine, the combination with the straight ticket bars, the universal bar operated by the latter and the automatic locking pawl, of the reciprocatory bar and connections between it and the pawl for releasing the latter when at its extremes of movement.

11. In a voting machine, the combination

with the universal bar and the automatic locking pawl coöperating therewith, the links coöperating with the pawl and the lever connected to one of them, of the reciprocatory bar having stops thereon coöperating with the link and lever to release the pawl at the extremes of movement.

WILLIAM J. LAUSTERER.
